No. 850,851.

PATENTED APR. 16, 1907.

E. RICHTER.

BLINDSTITCHING, OVERSEAMING, AND SERGING ATTACHMENT
FOR SEWING MACHINES.

APPLICATION FILED OCT. 31, 1906.

UNITED STATES PATENT OFFICE.

EDWARD RICHTER, OF NEW YORK, N. Y., ASSIGNOR OF ONE-THIRD TO GAR-
RITT H. OLIVER, OF NEW YORK, N. Y., ONE-THIRD TO MATTIE E. BULL,
OF GARWOOD, NEW JERSEY, AND ONE-THIRD TO CHARLES S. AMERMAN,
OF WASHINGTON, NEW JERSEY.

BLINDSTITCHING, OVERSEAMING, AND SERGING ATTACHMENT FOR SEWING-MACHINES.

No. 850,851.

Specification of Letters Patent.

Patented April 16, 1907.

Application filed October 31, 1906. Serial No. 341,414.

To all whom it may concern:

Be it known that I, EDWARD RICHTER, a citizen of the United States, residing in the borough of Brooklyn, city, county, and

5 State of New York, have invented a new and useful Improvement in Blindstitching, Overseaming, and Serging Attachments for Sewing-Machines, of which the following is a specification.

10 My invention relates to sewing-machine attachments of the kind that mechanically shift the work out of the path of the needle of the sewing-machine every other stroke, thereby enabling the operator to make any desirable fancy stitching, such as blindstitching, overseaming, or serging.

15 The object of my invention is to provide improved means for transmitting and converting the reciprocating motion of the 20 needle-bar of the sewing-machine to the required intermittent reciprocating motion of the work-shifting device at right angles to the plane of the needle.

25 The foregoing and other features of my invention will now be described in connection with the accompanying drawings, forming part of this specification, in which I have represented my attachment embodying the improvements in the preferred form, after 30 which I shall point out more particularly in the claims those features which I believe to be new and of my own invention.

35 Referring to the accompanying one sheet of drawings, in which similar characters of reference indicate like parts throughout the several views, Figure 1 is a plain view in part section of my improved attachment, showing the work-shifting device in extreme right position. Fig. 2 is an elevation of same. 40 Fig. 3 is a plan view similar to Fig. 1, showing the work-shifting device in extreme left position. Figs. 4 and 5 show my improved cloth-guiding device.

1 is the base-plate of my attachment.

45 2 is a housing for the working parts. In the drawings I have represented it to be cylindrical in shape, and for convenience of construction it is divided into two parts and fastened to each other and to the base-plate 1 by means of screws. On the inside of the 50 housing 2 are bearings 3 and 4, in which is movably mounted the shaft 5. Near one

end of this shaft 5 is mounted the cross-arm 6 at right angles to the shaft 5. On the other end and outside of the housing 2 is mounted 55 a crank 7, provided with a slot 8.

Vertically mounted in suitable bearings in housing 2 is the shaft or member 9, provided on its lower end with a cam 12. Directly above the cam 12 is a ratchet 13, which is engaged by the spring-pawl 14, mounted on lug 15 by means of screw 16. On the upper end of member 9 are mounted two cross-arms 10 and 11 at right angles to each other and at right angles to the member 9. The arms 10 65 and 11 are mounted so that when member 9 revolves they straddle the member 5 and alternately are engaged by arms 6.

17 is my work-shifting device, and consists of an L-shaped tongue slidably mounted in 70 slot or channel 20, the end of which is held in engagement with the face of the cam 12 by the spring 18, mounted at 19.

21 is the needle, and 22 is the reciprocating needle-bar of any sewing-machine. On 75 the needle-bar 22 is a pin 23, adapted to slide in slot 8 of lever 7, thereby oscillating the member 5.

The reciprocating motion of the needle-bar oscillates the shaft 5 and cross-arms 6, which 80 swing through an arc sufficient to engage first one of the cross-arms 10, then one of the cross-arms 11, mounted on shaft 9, and so on. This intermittently rotates the shaft 9 and the motion is made positive and definite by 85 the action of the spring-pawl 14 and ratchet 13. The rotating of this member 9, which is provided at its lower end with the cam 12, advances the spring-returned work-shifting device 17. As will be readily understood by 90 referring to the drawings, for every stroke of the needle-bar the cross-arms 6 of the oscillating member 5 describe two arcs, each time engaging one cross-arm of member 9, rotating that member ninety degrees. Two complete strokes of the needle-bar, therefore, 95 completely rotate the member 9 once, which reciprocates the work-shifting device. We now have reciprocating motion of the needle-bar reduced to half-time reciprocating motion of the work-shifting device at right angles, which is so timed that the work is pushed out of the path of the needle every other stroke or stitch just before the needle

is about to pierce the cloth and after the cloth has been advanced by any well-known means in any sewing-machine.

I will now proceed to describe the construction and action of my cloth-guiding device, as shown in Figs. 1 and 2 attached to the plate of my blindstitching attachment and in Figs. 4 and 5.

30 is a spring-plate eccentrically mounted 10 to base-plate 1 by the eccentric 31.

32 is a thumb-screw which screws into base-plate 1, passing through a slot in plate 30, the function of which is to guide and regulate the height of spring-plate 30.

15 On end of spring-plate 30 are two cloth-guiding faces 33 and 34 at right angles to each other, 33 being a horizontal plate, 34 a vertical plate. On the top of 33, pivotally mounted at 36, is an indicating-arm 37 with 20 pointer 38. The indicating-arm 37 is provided with a lip 40, which engages the pointer and carries it against the action of spring 42 into the graduated arc 39. When the indicating-arm is in contact with the needle 21, 25 any adjustment of the plate 30 by the eccentric 31 is indicated on the arc, as will be readily understood by referring to Figs. 1 and 4. The lip 41 on top of 33 is adapted to engage 30 lip 40 and prevent the indicating-arm from jarring into the path of the needle after it has been thrown out of position. (See Fig. 5.)

I wish it distinctly understood that my attachment herein illustrated and described is in the form which I desire to construct it and 35 that any changes or variations may be made as may be convenient or desirable without departing from the salient features of my invention, and I therefore intend the following claims to cover such modification as naturally fall within the lines of invention.

Having thus fully described my invention, what I claim as new, and desire to secure by Letters Patent, is—

1. In a machine of the character described, 45 the combination with a spring-actuated work-shifting device, an oscillating shaft provided with means to oscillate said shaft, cross-arm mounted on one end of said shaft, a rotating member provided with means to 50 reciprocate the work-shifting device, cross-

arms mounted at or near the top of said rotating member adapted to be engaged by the cross-arm of the oscillating member, whereby the oscillating member rotates the rotating member intermittently and in one direction. 55

2. In a sewing-machine attachment such as is used for blindstitching, serging, or overseaming, the improved means for imparting the required motion to the work-shifting device comprising a rotary member provided with two cross-arms, one of said arms passing through the rotary member a short distance below the other, an oscillating shaft provided at one end with a cross-arm adapted 60 to engage the cross-arms of the aforesaid rotary member, a work-shifting device adapted to be reciprocated by the aforesaid rotary member. 65

3. In a sewing-machine attachment such as used for fancy stitching, blindstitching, serging and overseaming, the improved means for imparting the required intermittent motion to the reciprocating work-shifting device, comprising a spring-returned work-shifting device, a rotary member provided with two through cross-arms, an oscillating member receiving its rocking motion from a reciprocating member of a sewing-machine, provided with a cross-arm adapted 70 to engage the aforesaid cross-arms of the rotary member whereby intermittent, unidirectional rotary motion is transmitted to the rotating member, a cam on said rotary member for periodically actuating the said work-shifting device, a cloth-guiding device provided with cloth-guiding surfaces and indicating means which, when brought into contact with a part of the sewing-machine shows the relative adjustment of the cloth-guiding surfaces to the extreme advance position of the 75 end of the reciprocating work-shifting device. 80

This specification signed and witnessed this 23d day of October, A. D. 1906.

EDWARD RICHTER.

In presence of—

MARGUERITE ROSS,
EDWD. VAN WINKLE.
